UNITED STATES PATENT OFFICE.

WILLIAM O. REW, OF EUREKA, CALIFORNIA, ASSIGNOR TO GOLDEN STATE MILK PRODUCTS COMPANY, OF SAN FRANCISCO, CALIFORNIA, A CORPORATION OF CALIFORNIA.

ATOMIZING NOZZLE.

Application filed May 17, 1918. Serial No. 235,130.

To all whom it may concern:

Be it known that I, WILLIAM O. REW, a citizen of the United States, residing at Eureka, in the county of Humboldt and State of California, have invented certain new and useful Improvements in Atomizing Nozzles; and I do hereby declare the following to be a full, clear, and exact description of the same, reference being had to the accompanying drawings forming part of this specification.

This invention relates to atomizing nozzles particularly those intended for use in desiccating milk products, the principal object being to provide a nozzle more efficient than those now in use and one which can be cleaned with great facility.

In the drawings,—

Fig. 1 is an elevation of the nozzle in place in the air duct which is shown in section.

Fig. 2 is a cross section on the line 2—2 of Fig. 1.

Fig. 3 is a vertical cross section through the center of the atomizing nozzle.

Fig. 4 is a vertical sectional view taken on the irregular line 4—4 of Fig. 3.

Fig. 5 is a view of the central core partly broken away to show the interior arrangement.

The atomizing nozzle includes a stem 1 connected to the main steam line 2 by a coupling 3 of the usual kind and joined at its other end to a head 4 which in turn is fastened to the central core 5 by a screw-threaded extension 6, the joint between them being provided with a metal gasket 7 preferably of lead to securely close the upper end of the ducts 8, equispaced about the central orifice 9 of the core, which orifice communicates at its upper end with the chamber 10 which is cut in the upper end of the core 5 to provide communication between the ducts 8 and the steam channel 11, the latter being flared as at 12 to direct the steam through the spaced ducts as well as through the central orifice 9. A plurality of radial holes 13 are spaced around the cylindrical end of the central core and communicate with an annular air space 14 surrounding the upper end of the main flaring orifice 9, in order to provide a circulation of air about this orifice and the ducts to cool the walls thereof. As best seen

in Fig. 4, the holes 13 are arranged in threes and are spaced between the vertical ducts 8, thereby carrying off a considerable quantity of heat. A ledge 15 closes the top of the chamber 14 against the steam and is securely brazed to the central piece 16 of the core, the necessity for this piece 16 being for convenience in forming the air chamber 14. The lower wall of the central core is bell-shaped, as at 17, to provide a flaring central orifice and the core is provided just above this point with threads 18 to which is attached an annular thimble 19 nearly cylindrical in form and co-operating with the flared end 17 of the core to provide a steam orifice 20, the size of the exit being adjusted by movement of the annular thimble on the threads. The core is also provided with a perforated lug 21, which rests on an annular ridge 23 on the shell member 23, the latter having a tapered annular wall 24 in close proximity to the lower end 25 of the annulus 19 and forming therewith a small annular air orifice 26 for the air chamber 27 formed between the upper wall 28 of the shell and the outer wall of the core and also between the lower tapered end 24 of the shell and the outer wall of the annulus 19, the two parts of this air chamber 27 communicating through the holes 29 in the lug 21. Secured to the threaded end 31 of a horizontal extension 32 of the shell member is a bowl member 33 having a tapered wall 34 narrowing towards the wall 24 of the shell to form a milk reservoir 34' and also having a vertical skirt or sleeve 35 perforated as at 36 to permit air to pass therethrough to the concentric orifices just described, but preventing a current of air from interfering with the operation of the nozzle. The bowl member 33 and also the cap member 37 which secures the shell to the head are provided with wrench holes 38 to aid in securely fastening the various parts of the nozzle together.

In order to space the nozzle in proper relation to the air tube 39 a spider 40 is provided consisting of a collar 41 loosely sliding on stem 1 and having mounted thereon a plurality of spacing members 42 for holding the nozzle approximately centrally of the air pipe. The shell member is provided as at 43 with a milk channel leading

to an upper milk pipe 44 integral therewith, which is threaded at its upper end to receive a milk conduit 45 leading from the main reservoir.

5 In operation, milk is led through the conduit 45, thence through the pipe 44 to the milk chamber 34' and forced out in the form of a fine spray through the narrow annular slit between the shell and the 10 bowl member. Steam is admitted through pipe 1 and at the top of the core separates into a plurality of streams partly passing through the flaring central orifice 9 and partly passing through the vertical ducts 8 which lead at their lower ends to the annular steam channel 20, the orifice of this channel directing the flow of the steam almost at right angles to the flow of the milk through its annular orifice. Air is admitted through the large holes 46 in the upper part of the shell member and passes partly into the air chamber 14 to cool the core member and also passes down the air chamber 27 and out the orifice 26 which is directed at an angle approximately midway between the angles of exit of the steam and milk. In this way the milk is discharged into the desiccating chamber in an extremely finely divided state enabling the 30 steam and heated air to readily extract all of the moisture present therein, depositing the solid material of the milk at the bottom of the desiccating chamber in a fine white powder.

25 35 What is claimed is:

1. In an atomizing nozzle, a central bore having a central orifice and a plurality of auxiliary orifices surrounding the central orifice, an air chamber closed at its forward 40 end and located between the central orifice and the remaining orifices, and a plurality of radial air passages leading to the air chamber between adjacent orifices.

2. In an atomizing nozzle, a plurality of

members providing a plurality of annular 45 orifices, an outer member having a tapered wall forming an additional orifice with said members and having a perforated skirt surrounding said orifices and preventing currents of air interfering with the action of the 50 atomizer.

3. A centrally perforated nozzle member having a plurality of discharge passages spaced about said central perforation, a bell mouth forming an extension of the central 55 passageway, and a cylindrical sleeve on said member to cooperate with said bell shaped extension to form a chamber into which said discharge passages lead.

4. A centrally perforated nozzle member 60 having a plurality of discharge passages spaced about said central perforation, a bell mouth forming an extension of the central passageway, and a cylindrical sleeve adjustably mounted on said member to cooperate 65 with said bell shaped extension to form a chamber into which said discharge passages lead and to provide an annular orifice from said chamber.

5. A centrally perforated nozzle member 70 having a plurality of discharge passages spaced about said central perforation, an air chamber closed at its forward end and located between the central perforation and the discharge passages and having an outlet 75 between two adjacent discharge passages.

6. A nozzle member having a central orifice, a plurality of parallel discharge passageways surrounding the central orifice and an annular air chamber located between said orifice and passageways, a flaring extension forming a continuation of said orifice, an annular sleeve cooperating with said extension to define a chamber the entrance to which is through said discharge passageways and the exit to which lies between said sleeve and said extension.

WILLIAM O. REW.
